UNITED STATES PATENT OFFICE.

ROBERT C. MOORE, OF KANSAS CITY, MISSOURI.

ELECTRIC SWITCH.

SPECIFICATION forming part of Letters Patent No. 694,977, dated March 11, 1902.

Application filed March 1, 1901. Serial No. 49,379. (No model.)

To all whom it may concern:

Be it known that I, ROBERT C. MOORE, a citizen of the United States, residing at Kansas City, Jackson county, Missouri, have invented a new and useful Electric Switch, of which the following is a specification.

My invention relates to switch mechanisms for electric systems, and particularly to that class which enable the operator in the central office to establish in a party-line or analogous system a private wire connection between the calling instrument and the one with which connection is desired.

My object is to produce an efficient and reliable switch mechanism of the class described which is of comparatively simple, compact, and inexpensive construction and which can be easily installed as a part of a new or as an improvement of an old system.

Before proceeding with the detailed description of the invention it is well to state that while my improved switch mechanism may be used in telegraph and electric-light or other electric systems it is designed, primarily, for use in telephonic systems, particularly those embracing a number of phones on the same line, known as "party-line" systems. For this reason when referring to the "phone" generally, particularly in the claims,

I use the term "service instrument" in order to avoid even the appearance of an undue limitation of the invention, it being understood when service instrument is referred to that it may be an electric light, a private telegraph apparatus, or a phone or any other instrument from which the subscriber of that particular station receives some service and which is operative electrically. For convenience the drawings and specification show and

refer to the apparatus only as used in connection with a telephonic system, and throughout said description the service instrument is termed a "phone" and its number is referred to as the "phone" number.

Essential elements in the production of an apparatus embodying the invention are enumerated below, the novelty of the invention depending to some extent on peculiarity of combination and peculiarities of construction of an apparatus capable of sending from one to any desired number of electric pulsations over a circuit supplementary or auxiliary to

the main-line circuit: A rotary disk for intermittent operation located at each subscriber's station or instrument and inscribed in a circle with numbers corresponding with the number of phones on the line and with two cam-notches in its periphery, one notch being located in radial alinement with the number indicative of its respective phone—such, for instance, as the number "6" of phone number 6, (see Fig. 2,) and the other or "home" notch at a distance from the first-named notch corresponding to the number of steps which the disk must take to reach the notch opposite the phone number—that is to say, in phone number 6 the home notch is located diametrically opposite the phone-number notch, while the notches of phone number 11 will be eleven steps apart, though appearing side by side, for the reason that the disk always rotates in the direction indicated by the arrow, Fig. 2; a vibratory contact operated by the disk to make and break the main-line circuit through the phone, said contact being insulated from the disk; an electromagnet located in the supplementary or auxiliary circuit or in the local circuit of the instrument and through which the course of the current is controlled by the central operator; a magnet-carrying lever to vibrate under the pulsations of current passing through the magnet; means for imparting to the disk an intermittent action through the medium of the magnet-carrying lever, and means for securing the disk against back rotation.

The normal condition of all the instruments is such that the home notches are all vertically above the axes of the disks, with the vibratory contacts consequently depressed and in circuit with their respective phones. Assuming now that a subscriber wishes to talk with the subscriber of phone number 6, he so notifies "central" in the usual or any preferred manner of that fact; but as his phone is already in circuit it should not be disturbed. The invention therefore consists, further, in means whereby the "calling" subscriber is enabled to hold his phone inactive as central sends the pulsations over the line, the effect of which is to synchronously rotate the disks of all the instruments except that of the calling subscriber. These pulsations, by reason of the registration of the

disk-notch indicative of phone number 6 with its respective vibratory contact, result in the depression of the latter and the establishment of the main-line circuit through the corresponding phone, (see Fig. 2,) all of the remaining phones, except, of course, that of the calling subscriber, which has remained inactive, and therefore in the main-line circuit, being thrown out of circuit by the engagement of their respective vibratory contacts with the conductors of the main line interposed between their respective phones and the source of electric energy, this non-registration of their vibratory contacts with their corresponding disk-notches resulting from the fact that said notches are either a fewer or greater number of steps from their home notches than is the notch of number 6. When the conversation is ended, central is notified of that fact in the usual or any preferred manner and imparts the necessary pulsations over the line to restore the phones to their original condition or the home notches, and all, therefore, in circuit with the main line. 25 As the calling subscriber's phone, however, had remained inactive during the first series of steps of the disks of the remaining instruments said subscriber could again hold his disk inactive until the other instruments were 30 restored to their original condition, when all would again be ready for operation. If the calling subscriber failed to hold his instrument during the steps necessary to restore the other instruments to their normal condition, it is clear that the disk of the calling subscriber's instrument would be rotated an insufficient distance and would therefore be 35 out of circuit with the remaining instruments, because of the non-registration with its vibratory contact of the notch indicative of its number, of which fact central would be ignorant, and, whether ignorant or not, powerless to correct. The invention therefore further consists in means whereby the calling subscriber whose disk is exposed to observation may mechanically impart the additional steps to restore his instrument to its original or normal condition, when the entire line would be intact and in proper working order. 45 50 The invention furthermore consists in means for preventing children or other unauthorized persons from tampering with the phone and either accidentally or maliciously throwing the same out of circuit, and therefore in such condition that the mistake must be rectified locally before said phone can be used.

With the general objects in view above mentioned the invention also consists in certain novel and peculiar features of construction and combinations of parts, as hereinafter described and claimed, and in order that it may be fully understood reference is to be had to the accompanying drawings, in which—

65 Figure 1 represents a diagrammatic view of an electric system embodying my invention, the switch-circuit being reinforced at each

subscriber's station by a battery. Fig. 2 represents an enlarged diagrammatic view of part of said system and shows circuits local to each instrument and provided with relays actuated by the switch-circuit. Fig. 3 is a face view of a casing with its door open, this casing containing the switch mechanism and reinforcing-battery of the switch-circuit, certain conductors of the main-line circuit also being located in the casing. Fig. 4 is a vertical section taken on the dotted line IV of Fig. 3. Fig. 5 is an enlarged horizontal section taken on the line V V of Fig. 6. Fig. 6 is a vertical section, on the same scale as Fig. 5, taken on the dotted line VI of Fig. 5. Fig. 7 is a sectional view showing the mechanism for imparting forward motion to and preventing back rotation of the disk hereinafter described. Fig. 8 is a detail perspective view showing more clearly the relation between the armature-carrying lever and the push-rod angle-arm, whereby the operation of the armature-carrying lever can be prevented, irrespective of whether the magnet is energized or not.

Similar reference-numerals designate corresponding parts in all the figures.

1 designates the main line of an electric system, which receives its electric energy from a dynamo or electric battery, as shown at 2, the phone 3 being interposed between a contact 4 and the battery, and a contact 5, preferably adjacent to contact 4, being interposed between the phone and the battery, these contacts being preferably located within a casing 6, forming a part of the phone-casing or secured adjacent thereto.

The phone comprises the transmitter A, the signal-mechanism-operating crank B, the hooked switch-lever C, and the receiver or hand phone D, communication being established with central by handling the operating-crank in the usual manner, this manipulation causing the annunciator E to notify central that the calling subscriber wishes to talk to central and obtain connection with some other subscriber. The operating-crank B, hooked switch-lever C, receiver or hand-phone D, and annunciator E appear only in Fig. 2, as they can be shown more clearly in said figure than in Fig. 1, as the latter is drawn to a considerably smaller scale.

7 designates a vibratory contact, the same being arranged to contact with contact 4 or with contact 5, in the latter case, of course, shunting the corresponding phone out of circuit, as will be readily understood by reference to Fig. 2, and attached to but insulated from this vibratory contact is a tooth 8, arranged to ride upon the periphery of disk 9 of its respective instrument, which disk is provided with a circular series of characters, preferably numbers, beginning with "0" and running as high as there are instruments in the line, each disk being provided opposite "0" with a home notch 10 and opposite the number indicative of its respective phone

with a notch 11. The tooth 8 of the vibratory contact rests in the home notch 10 when the instrument is in condition to be used or to be called into use, and when acting as the "called" instrument said tooth engages the notch 11 indicative of the phone number. The shaft of disk 9 is journaled in a suitable frame, as at 12, secured upon a shelf in casing 6, and rigidly secured to and at opposite sides of the disk are the ratchet-wheels 13 and 14, having their teeth disposed in opposite directions, a pivoted catch 15, mounted on the frame, serving to successively engage the teeth of wheel 14, and thus prevent back rotation of the disk. The ratchet-wheels are shown as provided with double the number of teeth as there are characters on the disk in order that it shall require two pulsations of current, as herein-after appears, to move the disk one step, or one-twelfth in this instance of a revolution; but it is to be understood that the number of teeth of the ratchet-wheels may correspond with the characters on the disk or may equal any other multiple of said characters than that shown. To impart movement to the disk, and to positively and reliably limit such movement, I provide a lever 16, carrying a pivoted spring-actuated pawl 17 engaging ratchet-wheel 14, and provided with a tooth 18 to engage ratchet-wheel 13, and positively limit each disk movement to exactly one step, a retractile spring 19 being employed to normally hold the lever with its tooth 18 out of engagement with ratchet-wheel 13, and its pawl 17 in position to impart movement to the disk as the lever rises, a stop 20 projecting from the frame serving to positively limit the movement imparted to the lever by said retractile spring. Secured to the opposite end of the lever is an armature 21 for an electromagnet 22, supported in any suitable manner within the casing and frame, (see Fig. 3,) said magnet being located in an electric circuit 23, local to the instrument, or in a circuit supplemental or auxiliary to and practically paralleling the main-line circuit, as hereinafter explained. The local circuit 23, as shown in Fig. 2, includes a battery, consisting of a plurality of cells 24, arranged within the casing 6, preferably, and below the shelf on which frame 12 rests. It also includes a relay 25 of the usual or any preferred construction, said relay being located in the supplemental or auxiliary circuit hereinbefore referred to, which circuit is herein designated by number 26, the source of electric energy for said circuit being a dynamo or a battery, as shown at 27, in the central office. This source of electric energy is preferably a battery, because where circuits local to the instrument are employed the current need only be sufficiently strong to operate the relays, which in the usual manner complete said local circuits and energize their magnets. In case, however, circuits local to the instrument are not established and the batteries 24 are located in and simply used to reinforce

or strengthen circuit 26 it will be obvious that the source of electric energy 27 may be weak or may be entirely dispensed with, or, on the other hand, said source of electric energy may be sufficiently strong to dispense with the batteries 24 local to the instrument. The form described and illustrated in Fig. 2 is that which is preferred and which, it is believed, will prove the most economical and satisfactory. Fig. 1 shows the system as arranged with the batteries 24 located in and reinforcing the current passing through circuit 26.

To energize the magnets the proper number of times, and therefore effect the desired adjustment of the disks, central may employ any suitable device or devices to make and break the circuit 26, and therefore send the necessary pulsations over the line; but in order to require as little attention from central as possible and to make the apparatus practically automatic I provide a switchboard 28, embracing a shaft 29, and an arm 30 upon said shaft and adapted to rotate in the direction indicated by the arrow, Fig. 2, under any suitable power, such as a clock-work, (not shown,) when not arrested by an obstruction in its path, such as a plug, hereinafter referred to or the pivoted catch 31, said catch being held normally in the path of the arm by means of a spring 32, suitably secured to the switchboard. This catch occupies a position on the switchboard corresponding to the home notch of the disks, the switchboard being provided with a circular series of holes 33, marked to correspond with the numbers on the disks indicative of the phone numbers, a suitable plug 34, hereinbefore mentioned, being adapted to be inserted by central in the hole opposite the character corresponding to the called phone—that is to say, assuming that phone number 6 has been called central instantly places the plug 34 in hole 6 and then presses against and withdraws catch 31 from the path of arm 30. As this takes place said arm rotates, as hereinbefore explained, until it strikes against and is arrested by said plug. In such progress it imparts twelve pulsations of current over the line and a corresponding number through the local circuit 23, if such circuits are employed. The magnets are then energized twelve times and impart a corresponding number of vibrations to the armature-carrying levers, which in turn, through the medium of spring-actuated pawls 17, rotate all of the disks except that of the calling instrument, held inactive by means herein-after described, a distance of six steps, equal to twelve steps of the ratchet-wheels. As a result the tooth 8 of the vibratory contact of the called instrument engages the cam-notch 6 of the disk of said instrument and conductor 4, thereby throwing the circuit through the corresponding phone, as indicated clearly in Fig. 2, the remaining instruments (except the calling instrument) being shunted out of cir-

cuit, because the cam-notches of their disks occur opposite their respective phone numbers and not opposite the characters corresponding to the called phone, the result being that the teeth 8 engage the peripheries of their respective disks and the contacts the conductors 5, interposed between their respective phones and the source of electric energy.

10 The specific means shown for sending the required pulsations over the line through the action of the rotating arm 30 is a disk 35, driven to make one complete revolution while arm 30 is passing from one character to another on the switchboard, said disk being provided with a hub 36, in constant engagement with a brush or conductor 37, located in circuit 26, and with a pair of diametrically opposite contact-lugs 38, each of which in one revolution of the disks makes and breaks the circuit through the brush or conductor 39, the intermediate mechanism between said shaft or driven arm 30 being a large friction-wheel 40 upon said shaft and a small friction-wheel 41 upon the shaft of disk 35 and engaging friction-wheel 40, as shown in Fig. 2. It is to be understood, however, that I do not restrict myself to any particular means for transmitting motion from shaft 29 to the shaft 30 of contact-disk 35, nor, in fact, to any special means under the control of central for sending the desired number of current pulsations over the line.

Referring now to means whereby the calling subscriber is enabled to hold his instrument inactive while central is synchronously throwing the called subscriber in and the remaining subscribers out of circuit, 42 designates a push-rod fitting slidingly in frame 12 (which frame, as shown, pivotally carries the vibratory contact 7 and the conductors 4 and 5) and embodying an angular portion 43, which prevents rotatable movement without interfering with longitudinal movement in the frame. Said push-rod is provided with a depending angle-arm 44, adapted to be interposed between the magnet and its armature-carrying lever, an expansive spring 45, however, serving to hold the rod with said angle-arm normally forward of and therefore out of the path of said lever. Said push-rod has its front end opposite the push-button 46 fitting in the door 47 of casing 6, so that as the push-button is pushed inward it shall strike and move the push-rod in the same direction, and therefore dispose the angle-arm 44 below the armature-carrying lever, and thus prevent the latter responding to the energization of the magnet. As the pressure is removed spring 47, spirally encircling the rod and bearing at its opposite ends against the door and the collar 48 of the push-button, restores the latter to its original position and permits spring 45 to readvance the push-rod 65 and move its angle-arm from below said lever.

Should the instrument of any particular subscriber be out of circuit with the remain-

ing instruments, he becomes aware of that fact by a glance at disk 9 through the transparent face-plate 49 of the door and restores his instrument to its proper position—viz., with the tooth 8 engaging the home notch of the disk (see Fig. 3)—by mechanically imparting the required number of movements to the armature-carrying lever. The means employed for this purpose consist of a vertical rod 50, mounted slidingly in frame 12 (see Fig. 6) and provided with a horizontal foot 51 at its lower end, overhanging the armature end of said lever, a spring 52 surrounding the rod and bearing at its opposite ends against the frame and the pin 53 or an equivalent device on the rod serving to hold the latter normally elevated, so that its foot shall not interfere with the free operation of said lever. The upper end of the rod projects through the top of the casing by preference and carries a push-button 54 thereon, by which it may be operated, and within the casing it is provided with a collar 55, for a purpose which hereinafter appears. By alternately depressing and releasing the push-button 54 it is obvious that the armature-carrying lever will be operated and will rotate the disk, the movement of the push-rod being continued until the tooth 8 of the vibratory contact enters the home or "0" notch, when the instrument is again in condition to serve as a calling instrument or to operate under pulsations of current sent out from the central office.

To prevent children or maliciously-inclined persons from throwing the instrument out of circuit by mechanically operating the disk in the manner described or by preventing the disk from operating when it should respond to impulses sent out over the line from the central office, I provide a locking mechanism constructed as follows:

56 designates a slide-bolt provided with slots 57, mounted on pins 58, projecting from the casing and serving as a guide and as a means for limiting the movement of the bolt. At its upper end the bolt is provided with the laterally-projecting arm 59 for sliding on the push-rod 50 beneath collar 55, and at its lower end it is provided with an arm 60, arranged to operate between the front end of the push-rod 42 and the push-button 46. The bolt is ordinarily disposed as shown in Fig. 6—that is, with its arm 59 against the under side of collar 55 and its arm 60 directly between push-rod 42 and push-button 46, being held in such position and also automatically thrown thereto by a spring 61, interposed between a lug 62 on the slide-bolt and a collar 63, mounted upon an adjusting-screw 64, carried by a lug 65, projecting from frame 12, said adjusting-screw being employed as a means for tensioning the spring when necessary. With the parts thus arranged it is obvious that the push-button cannot be operated and that consequently the disk cannot be mechanically moved or its movement imparted by electric

impulses sent out from the central office be interfered with. To overcome the resistance of said spring and unlock the bolt, a key is necessary, it being preferred, of course, that the key be of a peculiar type. In the drawings, to simplify the case as much as possible, a plain key 66 is employed, fitting in a keyhole 67 in the door and having its bit 68 adapted by pressure against lug 69 of the bolt to force the lock downward and hold it in such position against the action of spring 61 as long as the phone is in use. As soon as the conversation is ended the key is of course withdrawn and placed in a position inaccessible to children or unauthorized persons.

When a subscriber desires for any reason to throw his phone out of circuit—for instance, when he does not desire to be disturbed at night—he depresses push-button 54 once, this depression moving his disk one-half step beyond the home notch and therefore throwing the vibratory contact into engagement with conductor 5. The current therefore obviously passes from contact 7 through conductor 5 instead of passing through the phone.

From the above description it will be apparent that I have produced an electric switch embodying the features of advantage enumerated as desirable in the statement of invention, and while I have described and illustrated the preferred construction it is to be understood that it is susceptible of various changes without departing from its spirit and scope.

Having thus described the invention, what I claim as new, and desire to secure by Letters Patent, is—

1. In an apparatus of the character described, a main-line circuit, a "service" instrument therein—such for instance as a telephone, a movable contact to shunt said instrument in or out of said circuit, an auxiliary circuit, means for sending electric impulses therethrough, an electromagnet in said auxiliary circuit, an armature-carrying lever operated by said magnet and provided with a pawl, a ratchet-wheel engaged by said pawl, and a disk movable with said ratchet-wheel and numbered to correspond with the number of the "service" instrument or "phone" in the circuit, and provided with a home notch and a notch opposite the number indicative of the corresponding "service" instrument, the movable contact when engaged with or disengaged from either of said notches holding the "service" instrument in or out of circuit respectively.

2. In an apparatus of the character described, a main-line circuit, a "service" instrument therein—such for instance as a telephone, a movable contact to shunt said instrument in or out of said circuit, an auxiliary circuit, means for sending electric impulses therethrough, an electromagnet in said auxiliary circuit, an armature-carrying lever operated by said magnet and provided with

a pawl, a ratchet-wheel engaged by said pawl, a disk movable with said ratchet-wheel and numbered to correspond with the number of the "service" instrument or "phone" in the circuit, and provided with a "home" notch and a notch opposite the number indicative of the corresponding "service" instrument, the movable contact when engaged with or disengaged from either of said notches holding the "service" instrument in or out of circuit respectively, and means for holding said armature-carrying lever unresponsive to the energization of the magnet.

3. In an apparatus of the character described, a main-line circuit, a "service" instrument therein, a movable contact for shunting in or out of circuit said "service" instrument, an auxiliary circuit, means for sending electric impulses therethrough, an electromagnet to be energized by each impulse, an armature-carrying lever, means operated by said lever for causing said movable contact to throw the "service" instrument in or out of circuit with the main line, means for holding said armature-carrying lever unresponsive to the energization of the magnet, and means for mechanically operating said lever and thereby shunting said "service" instrument in or out of circuit.

4. In an apparatus of the character described, a main-line circuit, a "service" instrument therein—such for instance as a telephone, a movable contact to shunt said instrument in or out of circuit, an auxiliary circuit, means for sending electric impulses therethrough, an electromagnet in said auxiliary circuit, an armature-carrying lever operated by said magnet and provided with a pawl, a ratchet-wheel engaged by said pawl, a disk movable with said ratchet-wheel and numbered to correspond with the number of the "service" instrument or "phone" in the circuit, and provided with a home notch and a notch opposite the number indicative of the corresponding "service" instrument, the movable contact when engaged with or disengaged from either of said notches holding the "service" instrument in or out of circuit respectively, and means for preventing an unauthorized person from moving said movable contact and shunting the "service" instrument in or out of the main-line circuit.

5. In an apparatus of the character described, a main-line circuit, a "service" instrument therein, a movable contact for shunting in or out of circuit said "service" instrument, an auxiliary circuit, means for sending electric impulses therethrough, an electromagnet to be energized by each impulse, an armature-carrying lever, means operated by said lever for causing said movable contact to throw the "service" instrument in or out of circuit with the main line, means for holding said armature-carrying lever unresponsive to the energization of the magnet, means for mechanically operating said lever and thereby shunting said "service" instrument

in or out of circuit, and means for preventing an unauthorized person from moving said movable contact and shunting the "service" instrument in or out of the main-line circuit.

5 6. In an apparatus of the character described, a main-line circuit, a contact therein, a "service" instrument interposed between the contact and the source of electric energy, a second contact interposed between the instrument and the source of electric energy, a movable or vibratory contact to engage one or the other of said contacts, a rotary disk containing a character indicative of the number of said "service" instrument, and a notch 15 opposite said character, a tooth attached to but insulated from the movable or vibratory contact, and when engaging the notch, permitting the contact to engage the contact between which and the source of electric energy 20 is located the "service" instrument, and means for rotating said disk and thereby throwing said tooth out of the notch and causing the vibratory contact to engage the other contact and shunt the "service" instrument 25 out of the main-line circuit.

7. In an apparatus of the character described, a main-line circuit, a contact therein, a "service" instrument interposed between the contact and the source of electric energy, a second contact interposed between the instrument and the source of electric energy, a movable or vibratory contact to engage one or the other of said contacts, a rotary disk containing a character indicative of the number of said "service" instrument, and a notch 30 opposite said character, a tooth attached to but insulated from the movable or vibratory contact, and when engaging the notch, permitting the contact to engage the contact between which and the source of electric energy 35 is located the "service" instrument, a lever for intermittently rotating said disk, and thereby throwing the vibratory contact in engagement with one of said contacts or the other, and mechanically-operated means for oscillating said lever, substantially as described.

8. In an apparatus of the character described, a main-line circuit, a contact therein, a "service" instrument interposed between the contact and the source of electric energy, a second contact interposed between the instrument and the source of electric energy, a movable or vibratory contact to engage one or the other of said contacts, a rotary disk 50 containing a character indicative of the number of said "service" instrument, and a notch opposite said character, a tooth attached to but insulated from the movable or vibratory contact, and when engaging the notch, permitting the contact to engage the contact between which and the source of electric energy 55 is located the "service" instrument, a lever for intermittently rotating said disk, and thereby throwing the vibratory contact in engagement with one or the other of said contacts, and a push-button for operating said lever, substantially as described.

9. In an apparatus of the character described, a main-line circuit, a contact therein, a "service" instrument interposed between the contact and the source of electric energy, a second contact interposed between the instrument and the source of electric energy, a movable or vibratory contact to engage one or the other of said contacts, a rotary disk 70 containing a character indicative of the number of said "service" instrument, and a notch opposite said character, a tooth attached to but insulated from the movable or vibratory contact, and when engaging the notch, permitting the contact to engage the contact between which and the source of electric energy 75 is located the "service" instrument, a lever for intermittently rotating said disk, and thereby throwing the vibratory contact in engagement with one or the other of said contacts, and mechanically-operated devices for preventing the operation of said lever, substantially as described.

10. In an apparatus of the character described, a main-line circuit, a contact therein, a "service" instrument interposed between the contact and the source of electric energy, a second contact interposed between the instrument and the source of electric energy, a movable or vibratory contact to engage one or the other of said contacts, a rotary disk 90 containing a character indicative of the number of said "service" instrument, and a notch opposite said character, a tooth attached to but insulated from the movable or vibratory contact, and when engaging the notch, permitting the contact to engage the contact between which and the source of electric energy 95 is located the "service" instrument, a lever for intermittently rotating said disk, and thereby throwing the vibratory contact in engagement with one or the other of said contacts, mechanically-operated devices for preventing the operation of said lever, substantially as described.

11. In an apparatus of the character described, a main-line circuit, a contact therein, a "service" instrument interposed between the contact and the source of electric energy, a second contact interposed between the instrument and the source of electric energy, a movable or vibratory contact to engage one or the other of said contacts, a rotary disk 110 containing a character indicative of the number of the "service" instrument, and a notch opposite said character, a tooth attached to but insulated from the movable or vibratory contact, and when engaging the notch, permitting the contact to engage the contact between which and the source of electric energy 115 is located the "service" instrument, a lever for intermittently rotating said disk, and thereby throwing the vibratory contact in engagement with one or the other of said contacts, mechanically-operated devices for preventing the operation of said lever, substantially as described.

venting the operation of said lever, means for automatically preventing the last-named devices from being actuated by an unauthorized person to interfere with the free operation of 5 said lever, and a key for withdrawing said automatic devices to inoperative position, substantially as described.

12. In an apparatus of the character described, a main-line circuit, a contact therein, a "service" instrument interposed between the contact and the source of electric energy, a second contact interposed between the instrument and the source of electric energy, a movable or vibratory contact to engage one 15 or the other of said contacts, a rotary disk containing a character indicative of the number of said "service" instrument, and a notch opposite said character, a tooth attached to but insulated from the movable or vibratory 20 contact, and when engaging the notch permitting the contact to engage the contact between which and the source of electric energy is located the "service" instrument, a lever for intermittently rotating said disk, 25 and thereby throwing the vibratory contact in engagement with one of said contacts or the other, mechanically-operated means for oscillating said lever, mechanically-operated means for preventing said lever from operating, 30 an automatic device for preventing the last-named means from interfering with the operation of the lever and for preventing the means for operating the lever from operating the same, and means to withdraw said 35 automatic device to an inoperative position, substantially as described.

13. In an apparatus of the character described, a main-line circuit, a "service" instrument therein, a movable contact to shunt 40 said "service" instrument in or out of circuit, an auxiliary circuit, an electromagnet therein, an armature for the magnet, instrumentalities interposed between the armature and the movable contact whereby the latter is caused to shunt the "service" instrument 45 in or out of the main-line circuit, and means for sending the required number of electric impulses over the line, the same comprising a rotating arm, a movable catch to automatically arrest said rotating arm at the completion 50 of each revolution thereof, a plate provided with holes arranged in a circular series and in number equaling the number of "service" instruments, and a pin to removably engage one of said holes and thus arrest 55 said arm before it has completed a revolution.

14. In an apparatus of the character described, a main-line circuit, a plurality of "service" instruments therein, movable contacts to shunt said "service" instruments in 60 or out of circuit with the main line, rotary disks for said instruments, provided with characters indicative of the number of said "service" instruments, each disk being provided with a "home" notch, and with a notch 65 opposite the character indicative of the number of its respective "service" instrument,

teeth insulated from and carried by said movable contacts and adapted to engage alternately, the notches and the peripheries of 70 said disks, an armature-carrying lever for imparting intermittent action to said disks, an auxiliary circuit, an electromagnet therein, and means for sending the required number of electric impulses therethrough for causing 75 the registration of the character-notch of a particular disk with the tooth of its respective movable contact.

15. In an apparatus of the character described, a main-line circuit, a plurality of 80 "service" instruments therein, movable contacts to shunt said "service" instruments in or out of circuit with the main line, rotary disks for said instruments, provided with characters indicative of the number of said 85 "service" instruments, each disk being provided with a "home" notch, and with a notch opposite the character indicative of the number of its respective service instrument, teeth insulated from and carried by said movable 90 contacts and adapted to engage alternately, the notches and the peripheries of said disks, an armature-carrying lever for imparting intermittent action to said disks, an auxiliary circuit, an electromagnet therein, means for sending the required number of electric impulses therethrough for causing the registration of the character-notch of a particular disk with the tooth of its respective movable contact, and means for mechanically operating 95 the disk of a particular instrument.

16. In an apparatus of the character described, a main-line circuit, a plurality of "service" instruments therein, movable contacts to shunt said "service" instruments in 105 or out of circuit with the main line, rotary disks for said instruments, provided with characters indicative of the number of said service instruments, each disk being provided with a "home" notch, and with a notch 110 opposite the character indicative of the number of its respective service instrument, teeth insulated from and carried by said movable contacts and adapted to alternately engage the notches and the peripheries of said disks, 115 an armature-carrying lever for imparting intermittent action to said disks, an auxiliary circuit, an electromagnet therein, means for sending the required number of electric impulses therethrough and for causing the registration 120 of the character-notch of a particular disk with the tooth of its respective movable contact, means for mechanically operating said disk of the particular instrument, and means for holding inactive the disk of a particular instrument, against the energization 125 of its magnet, substantially as described.

In testimony whereof I affix my signature in the presence of two witnesses.

ROBERT C. MOORE.
